FIG. 10

William E. Drummond

UNITED STATES PATENT OFFICE

2,047,014

WALL CONSTRUCTION

William E. Drummond, River Forest, Ill.

Refiled for abandoned application Serial No. 683,193, August 1, 1933. This application October 24, 1935, Serial No. 46,636

21 Claims. (Cl. 72—16)

This invention relates to improvements in rib stiffened walls of the type having blocks joined in forming a flush surface at one side of the wall and on the other, a surface having reenforcing 5 ribs extending between projecting pilasters, the end portions of the blocks together with the associated pilaster facing material forming vertical shafts adapted to be filled with concrete and steel reinforcement and improved means of securing the members together, and the objects of my invention are as follows:

To provide block units that may be made of concrete, terra cotta and the like and joined in a wall without using mortar;

15 To provide block units having built-in attachment portions that may be readily employed in securing the units in a wall;

To provide units that may be dismantled from and re-used in wall construction with a minimum 20 of reconditioning;

To provide units adapted to the building of walls of structures wherein the units may either be permanently retained as first erected or may 25 be used in part as forms, in the latter case enabling the builder to produce walls more secure against exposure to fire and better able to resist stress merely by the additional operation of placing the concrete-steel fill required having the released forms in hand to offset the cost of filling 30 and stripping;

To provide units that may be joined in erecting walls of structures wherein the outer enveloping portion is connected to and supported by interior- 35 located structural members by means of a relatively small cross-sectional area of attaching material, thus to minimize the passage of sound and heat waves through the structure.

I attain these objects by the structural elements illustrated in the accompanying drawings 40 in which—

Fig. 1 is an elevation showing four courses of block units (hereinafter called blocks) arranged so as to expose their ribbed faces in a wall together with two U-shaped pilaster form units 45 (hereinafter called studs) and showing the visible portions of the means of connecting the units;

Fig. 2 is a section taken on the line 1—1 of Fig. 1 showing the transverse relation of blocks and studs and in dotted lines a lap joint in the 50 stud;

Fig. 3 is a section taken on the line 2—2 of Fig. 1 showing the horizontal relation of assembled blocks and studs;

Fig. 4 is an elevation showing four courses of 55 blocks arranged so as to have their plane faces

flush and their edges in contact in a wall surface (hereinafter called the outside) together with the outer side of two studs as extended above and at the inner side of the courses;

Fig. 5 is a section, on a large scale, taken on the line 3—3 of Fig. 1 showing a partial concrete-steel fill and insulation lining within the space formed by two of the associated blocks and a stud (hereinafter called shaft);

Fig. 6 is an enlarged elevation of the portion 10 of the inside of the wall shown within the outline 4 of Fig. 1 and showing in addition in dotted lines reenforcing rods and the anchor extended.

Fig. 7 is a front view perspective illustrating the appearance of portions of two blocks at a 15 connection, such as illustrated in Fig. 6, but with parts separated so as to show one block in an overpoised position, wherein its pin hole is located off center with respect to the vertically aligned pin holes in the anchor and the other block, the 20 anchor is poised between the two blocks and the connecting pin has its tapered portion located in the hole of the overpoised block and its point inserted off center in the pin hole of the anchor, its shank standing within the groove in the over- 25 poised block;

Fig. 8 is a section on a large scale, taken on the line 5—5 of Fig. 1;

Fig. 9 is a perspective view of the inner side and top edge of one of the units of board insulating material used to line the inner surface of each coursed pair of the blocks in the shaft and in dotted lines portions of other such units shown in vertically aligned contact;

Fig. 10 is a perspective of a block unit showing 35 the inner side, butt and bed edges of a block unit.

Aside from such blocks of special shape, as may be required to finish courses at wall openings, corners and the like, or where walls are curved in plan, there need be employed blocks of this 40 construction having but one size to form the surfaces of the exterior portion of the enclosing walls of any structure wherein the center to center spacings of the studs is equal to the length of the block used and wherein height dimensions 45 are multiples of the block height, and it will be seen in referring to Figs. 1, 2, 3, 4 and 5, that the studs 6, 6 when secured at top and bottom as in a building, are the wall stiffening members, while the blocks 7, 7, each having pin 8 and anchor 9 50 connections to the studs 6, 6 form the shaft 10. Each block has at one side a rectangular plane face 11 exposed in the outside surface of the wall as seen in Fig. 4, with edge portions meeting in bed joints 12, 12 and butt joints 13, 13, each joint 55

surface being disposed at a right angle to the outside and on the inside in a surface comprising two mid-portions of which one, having a plane rectangular face 14 parallel to the outer face 11, 5 limits the relatively thin central portion 15 of the block 7 and is bordered on four sides by the other a rib portion 16 of convex profile enclosing reenforcing rods 17, 17 and which limits the block vertically as the curve of its profile 18 10 becomes horizontally tangent at the bed joint 12 with the joint clearance surface 19 which extends the length of the block adjoining the bed joints 12, 12 and terminates laterally at each end in portions having concavely splayed vertically 15 disposed surfaces 20, 20 which are exposed in the shaft 10 and form in association with like portions of joining blocks, the outer structural wall of the shaft, the splayed surfaces 20 being terminated at either end of the block in a relatively thin portion 21 forming the butt edge of the block and at the inner side forming at a wide angle the shoulder portion 22, the latter having a relatively narrow surface 23 exposed between the splayed face 20 and the adjoining verge of 25 the quadrilateral rib 16, each shoulder where terminated by the horizontally disposed joint clearance surface 19 having embedded within its surface a flush relatively thin metallic bearing plate 24, as seen in Figs. 6, 7, 8 and 10, each plate 30 being pierced by a circular pin hole 25 located equally distant from the outside and from each adjoining butt joint 13, the bearing plates 24 each being associated with an in-curving vertically disposed notch-like groove 26 of semi-circular profile located immediately adjacent in the shoulder portion 23 and having its deep end butting against the plate 24, the surfaces of the joint 35 clearance space 19 containing the bearing plates 24, having at their outer verge, as illustrated in Fig. 8, a slightly rebated relation to the bed joint portion 27 extending at each edge horizontally lengthwise the block of a width equal approximately to the width of the surface of the butt joint 13 and within these edge surfaces the block 40 is composed to a relatively slight but uniform depth, of a resilient substance 28, such as mineral wool filled with a mixture of asphalt and mineral oil. The leg portions 29, 29 of each of the U-shaped studs 6, 6 extend substantially at a right 45 angle to the wall, each having a flange 30 extending laterally at the near edge 31, the inner surface of the flange 30 being in contact at the extreme edge 32 with the shoulder portion 23 of the block, the leg portions 29, 29 and the closed 50 portion 33 opposite to the flanges forming three of the four walls of the shaft 10. As means of securing a more or less rigidly fixed relation between the extreme leg portions 29, 29 of the stud 6 cylindrical tubes 34 are disposed in spaced plurality adjacent the flanges 30, 30 horizontally parallel to the wall face 11 and extending across the shaft 10 to its walls 29, 29 each enclosing a bolt 35 which passes thru the shaft walls 29, 29 55 and is drawn up, these separators—being plural- 60 ly located in the lap-joint portion 36 of each stud 6 having plural sections and wherein the outer surfaces of one section lie against the inner surfaces of the other and wherein one section has separator bolt holes 37, 37 in a closely spaced 65 plurality, so as to provide plural locations at which member may be secured in adjusted length 70 as shown in Fig. 2.

Twisted strap anchors 9, 9 such as illustrated in Fig. 5 partly in dotted lines, each having a 75 vertically disposed mid-portion 39 and horizon-

tally disposed end portions 40, 40 of uniform thickness, are slidably mounted on the flanges 30, 30 of the studs 6, 6 by means of recesses 41, 41 provided at the inner side of the end portions 40, 40, each having at the rear extremity a shoulder 42 positioned against the wall 29 of the shaft 10 and at the far extremity, a shoulder 43 having a re-entrant angle to the recess 41 and which passes around and engages the outer edge of the flange 32, the end portions 40, 40 each extending laterally so as to be positioned in the joint clearance space 19 between the oppositely located bearing plates 24 in subjacent and superimposed blocks and being pierced with a hole 44 concentric with and of the same diameter as the holes 25 15 in the bearing plate 24. A pin 8 having a relatively long tapered portion 45 terminating in a point 46 and having a shank 47 of circular profile the surface of which will circularly contact the walls of the vertically concentric holes 25, 44, 25, 20 in passing thru them forms the connection between the blocks 7, 7 and the anchor 9.

Insulating board units 48, 48 such as illustrated in Fig. 9 having a curved profile may be employed to line the outer wall side 20 of the shaft 25 10, each unit 48 as seen in Fig. 5 being in contact at its outer surface 49 with the inner surfaces of two adjacent blocks 20, 20, in contact at its two splayed portions 50, 50 with the corresponding outer surfaces of the stud flanges 30, 30 30 and with its inner surface 51 exposed in the shaft 10 and extending between the side walls 29, 29 thereof, the unit being so shaped at each of its four corner portions 52, 52 as to preserve a clearance 53 approximately equal to the dimensions of 35 a fill which may be provided around the anchors within the shaft 10.

The walls 54, 54 of the groove 26 in the shoulder portion 23 of the blocks 7, 7 are each so formed that as the shank 47 of the pin 8 is inserted lengthwise the groove 26, then thru hole 25 of the adjoining bearing plate 24 only a slight lateral clearance 55 is provided between the shank portion 47 and the groove wall 54 when assuming a correct "set" position wherein the shank portion 45 only is engaged in the holes 25, 25, until this position is nearly reached the head portion of the pin may contact the inner face portions of the walls 54, 54 in being slidably guided in a curvilinear direction. Thus guided a misdirected hammer stroke may be applied on the head with difficulty and the pin normally needs not to be secured from deflection by other means.

In order to exert pressure on the butt joints spanned by the anchor after a block is located in 55 an approximately correct position, such pressure may be had by means of the "drift" to be obtained by the combination of offset holes, tapered pin 8 and groove 26. Assume, as illustrated in Fig. 7, that a pin has penetrated the 60 hole 25 in the plate 24 of an over-poised block having an offset relation to a block secured in a wall, between these a secured anchor is poised, now when the overpoised block and anchor are dropped in place it may be assumed that the 65 anchor hole 44 will be concentric with the plate hole 25 below and offset from the plate hole 25 above and that the pin point 46 has held its relative position with reference to the anchor hole 44, consequently if the pin 8 is driven downward, the wedge action of the tapered portion 45 must press slidably against the fixed anchor hole 44 wall outwardly of the butt joint 13 and against the wall of the block plate hole 25 oppositely also, but in much less degree, against the restraining 70 75

groove wall 26 with the effect of moving the free block 7 toward the joint 13 as the tapered portion of the pin progresses downward, thus in setting blocks any offset relation will be overcome by the use of the pins, all of the blocks being progressively anchored in adjusted alignment to the several studs as shown in Fig. 4 when and as the latter are retained in plumb condition.

The end portions of the anchors 9, 9 may be made of such thickness as will preserve a relatively small clearance between the upper and nether joint clearance surfaces 19, 19 so that should the resilient portions 28, 28 of the blocks at the horizontal joints 12, 12 yield to any pressure and consequently cause decrease in the clearance of the anchors 9, 9—the latter, if pressed upon, may assume the load and transfer it directly to the shoulders of the adjacent blocks, thus in arresting the movement, any excessive extrusion of the resilient substance 28 will be prevented, any vertical movement between the studs 6, 6 and the joined blocks 7, 7 being "taken up" by means of the slidable grip of the anchors 9, 9 on the studs 6, 6.

In using these units to erect a wall, studs 6, 6 of a length appropriate to the wall height may first be set up and braced in plumb aligned condition and in such spaced relation as corresponds to the length of blocks to be used, whereupon after the first course is secured in horizontal alignment, the blocks may be set in place in courses, securing each block at its bed joint in the manner above explained, while temporarily employing means to yoke an upper portion of the block to an adjacent stud.

Prior to the erection of the studs the strap anchors 9, 9 may be mounted on the flange portions 30, 30 of the studs 6, 6 in such spaced relation that as the courses are placed an anchor 9 will be positioned near to and immediately above each bed joint 12 line so that when blocks are set an anchor 9, may in each case be availed of merely by driving it downward and onto the upper edge of the block to be secured.

Before mounting the anchors 9, 9 on the flanges 30, 30 of the studs 6, 6, the prong-like portions 43, 43 may each be bent backward more or less upon itself so as to allow the recessed portions 41, 41 of the anchor 9 to lie against the outer faces of the flanges 30, 30, with the shoulders 42, 42, 43, 43 engaging the edge portions 31, 31, 32, 32, whereupon the prong portions 43, 43 may be again bent so as to hold the anchor 9 to the stud member 6.

It will be noted that for structural purposes the following are among some of the advantages to be had by the use of these units:

Due to accessibility, the condition of connecting portions may be examined, tested and, if necessary, repaired before being concealed;

Due to adaptability, if the shaft at any stud be filled at any time subsequent to securing of the blocks, the spaces formed around and about each connecting anchor and shoulder portion may also be filled, thus at one operation, keying the blocks in a preferred state of settled adjustment and creating a minimum of relatively small but strongly reinforced concrete portions rigidly connecting the otherwise separated inner and outer elements of a strong wall having inbuilt and effective insulation properties when the studs have been removed;

The separators remaining in the pilasters may be utilized for the connecting of joist and rafter

hangers and the like if the shafts have been filled;

The material composing the studs may be formed of sheet metal having such an out-sprung profile, that when the retaining bolts and anchor prongs are removed, the potential energy characteristic of the steel will act tending to spring the form walls away from the cast concrete of the pilaster, thus assisting in form stripping;

The spaces surrounding the anchors at the indented portions of the insulating units may be plugged so as to prevent the passing of concrete, thus deferring the solid enclosure of anchor connections until if and when settlement of temperature conditions make such filling desirable;

The blocks may be made under such controlled conditions of composition, humidity, temperature and pressure and have such surface treatment, that uniformity of strength giving and waterproof qualities, together with a preferred condition of viscosity in the edging substance may be secured;

All cast members in a wall that has been "filled" may readily be disconnected and their use extended indefinitely if such substances be applied at all contacting surfaces at the time of erection as will limit adhesion between them;

The studs may receive steel angle reenforcing members of relatively large dimensions thus adapting them for use in very high unattached wall constructions;

If the insulative units be omitted, and the released space filled with concrete, greater relative strength and rigidity may be secured;

The steel reenforcement in the rib portions of the blocks may each be shaped in the outline of a rectangle having extensions reaching to and comprising the bearing plates 25, 25 each shoulder of the block, thus producing a continuation of reenforcement means coextensive with each wall surface economically disposed so as to resist lateral force tending to displace members and cause it to be diverted into diagonal reaction against a large number of more or less resilient factors;

The blocks may be set having mortar joints if desired; and

The studs may be employed with other anchored-in wall facing units such as bricks, stones, blocks and the like.

This application constitutes a refiling of applicant's abandoned application, Serial No. 683,193, filed Aug. 1, 1933.

I claim as my invention and desire to secure by Letters Patent:

1. In a wall constructed of building block units, arranged in horizontal and vertical alignment, anchors disposed bilaterally from the butt joints in the bed joints having at either end portions a perforation, thru each perforation a pin, the pin passing thru adjacent portions of subjacent and superimposed blocks wherein and whereat are located grooves disposed at an angle to the bed joint thru which the pin may be inserted or withdrawn, the combination providing accessible means of securing four blocks each to the other at any intersecting, horizontal and vertical joining.

2. In a wall constructed of building block units arranged in horizontal and vertical alignment and structural members extending adjacent to and in parallel relation with the butt joints, anchors extending bilaterally from the structural members in the bed joints of the blocks each having

at either end portion a perforation, through each perforation a pin, the pin passing thru adjacent portions of subjacent and superimposed blocks wherein and whereat are located grooves disposed 5 at an angle to the bed joint thru which the pin may be inserted or withdrawn, the combination providing accessible means of securing four blocks each to the other and to any structural member at any intersecting horizontal and vertical joining.

10 3. In a wall constructed of building block units arranged in courses, in each bed joint a plurality of securing means such as anchors, each having perforated end portions, thru each perforation a pin projecting at an angle to the joint from upper and nether surfaces of the anchor, oppositely pierced by each pin a thinned portion of each subjacent and superimposed block, each having extending beyond the perforated portion clearance 15 for inserting or withdrawing the pin, the combination providing accessible means of securing a plurality of blocks each to another at any bed joint.

20 4. In a wall constructed of building block units arranged in horizontal and vertical alignment and structural members extending adjacent and in parallel relation with the butt joints, secured to and extending bilaterally from each structural member in each bed joint securing means such 25 as anchors, each having perforated end portions thru each perforation a pin projecting at an angle to the joint from upper and nether surfaces of the anchor, oppositely pierced by each pin a thinned portion in each adjacent and superimposed block, 30 each having extending beyond the perforated portion clearance for inserting or withdrawing the pin, the combination providing accessible means of securing a plurality of blocks each to another and to the structural member at any bed joint.

35 40 5. In a wall constructed of building block units arranged in horizontal and vertical alignment and structural members extending adjacent and in parallel relation with the butt joints, secured to and extending bilaterally from each structural member in each bed joint securing means such 45 as anchors, each having perforated end portions thru each perforation a pin projecting at an angle to the joint from upper and nether surfaces of the anchor, oppositely pierced by each pin a metallic 50 plate secured in adjacent portions of each adjacent and superimposed block, each having extending beyond the perforated portion clearance for inserting or withdrawing the pin, the combination 55 providing accessible means of securing a plurality of blocks each to another and to the structural member at any bed joint.

60 6. In a wall constructed of block units arranged in horizontal and vertical alignment, in each bed joint a plurality of securing means such as strap anchors, each having perforations near their end portions, similar perforations in immediately subjacent and superimposed portions of associated blocks, the walls of the three associated perforations combining to form a shaft disposed at 65 an angle to the bed joint, in each shaft a pin, the shank of each pin in contact with the wall of the perforation in the anchor farthest removed from the butt joint and with the walls of the perforations nearest to the butt joints in each of the blocks, the combination providing means of securing the anchor to the blocks at intersecting joints.

70 75 7. In a wall constructed of block units arranged in horizontal and vertical alignment and

structural members extending adjacent and in parallel relation to the butt joints, in each bed joint a plurality of perforated securing means such as strap anchors extending bilaterally from each structural member, similar perforations in immediately subjacent and superimposed portions of associated blocks, the walls of the three perforations combining to form a shaft disposed at an angle to the bed joint, in each shaft a pin, the shank of each pin in contact with the wall 10 of the perforation in the anchor farthest removed from the butt joint and with the walls of the perforation nearest to the butt joints in each of the blocks, the combination providing means of securing the anchor to the blocks at intersecting 15 joints.

8. In a wall constructed of block units arranged in horizontal and vertical alignment and structural members extending adjacent and in parallel relation to the butt joints, in each bed joint a plurality of perforated securing means such as strap anchors extending bilaterally from each structural member, similar perforations in immediately subjacent and superimposed portions of associated blocks, the walls of the three associated perforations combining to form a shaft disposed at an angle to the bed joint as each overpoised block is being positioned, means to force the holes into predetermined lateral relationship such as drift pins, each having an elongated tapered end portion terminating in a point which may be inserted in the shaft point first and driven so as to force the shank portion into the shaft so far as to be in contact with the wall of the perforation in the anchor farthest removed 35 from the butt joint and with the walls of the perforation in each of the blocks nearest to the butt joints, the combination providing means to overcome any offset relation in adjusting overpoised blocks to blocks secured.

40 9. In a wall constructed of block units having perforated anchor portions located in bed joints, oppositely located in immediately subjacent and superimposed portions of associated blocks, portions such as perforated anchorage plates, the 45 perforations in the anchor and those in the adjacent plate portions of the blocks forming a shaft, extending at an angle from the plate holes in either block straightly opposite the bed joint, a groove, standing with its point engaged in the 50 shaft and with its head more or less in contact with the wall of the inner portion of a groove, a drift pin, the combination providing means of maintaining the pin at a preferred angle to the bed joint while having its tapered portion driven 55 within the shaft.

10. In a wall comprising block units forming members in and at one face and having continuously aligned bed and butt joints and U-shaped structural members each positioned immediately adjacent and in parallel relation to a butt joint, with leg portions extending outward from the wall and enclosing in connection with the blocks a shaft, securing means extending to and between the associated members at the intersecting bed and butt joints, the combination effecting a rigidly constructed wall.

11. In a structure having block units of rectangular shape associated in a wall, U-shaped vertical structural members each positioned on one side of the wall, the leg portions having flanges outwardly disposed paralleling and in contact with the wall face, securing means such as strap anchors extending laterally from flanged 75

leg portion to flanged leg portion, thence and at either side, in horizontal disposition to and beyond the outer edge portions of the flanges each in edgewise contact with the outer face of a flange and having an extended offset portion contacting the inner shoulder of the flange and an extended offset portion having a re-entrant angle portion connecting with and obliquely engaging the outer edge of the flange portion of the leg 10 of the structural member, the anchor extending as securing means to the associated blocks, the combination forming means of slidably connecting the anchor to the structural member.

12. In a wall structure comprising within and at one surface block units, and within and at the other extending from the bottom to the top thereof in spaced plurality members having a cross-sectional profile of U-shape, the extreme leg portions of which butt against the wall, securing 20 means extending between the leg portions of the members and the associated blocks and extending horizontally between the leg portions of each of the members in spaced plurality parallel to the wall, cylindrical tubes each having end portions 25 positioned against the inner face of either leg portion, bolts passing thru the walls of the leg portions and transversely thru the tubes, the combination securing the leg portions each to the other in a more or less rigidly fixed relation 30 capable of resisting lateral movement when the member is loaded.

13. In a wall structure comprising within and at one surface block units and secured to these within and at the other surface a spaced plurality 35 of U-shaped structural members the extreme leg portions of which butt against the wall each being in units comprising two or more sections, each section being an extension from one adjoining section, the two having a joint portion wherein 40 one section lies within the other with the outer surfaces of its leg portions and closed side more or less in contact with the corresponding inner surfaces of the leg and closed portions of the other, the leg portions of both having separator 45 bolt holes arranged longitudinally in spaced alignment oppositely disposed in the legs of each, plural separator-connector units securing the lap-joint portions of the members, the combination 50 providing members capable of adjustment to lengths limited by the number of combined positions in which the sections have connector holes in register in the lap-joint portions.

14. In a wall structure comprising block units at and within one flush surface and vertically disposed in spaced plurality within and at the other, U-shaped flange edged structural members, securing means extending between the members, bolts extending between the side wall portions of the legs of the U-shaped member within separator 60 shells, being utilized to secure in a deformed drawn-together condition the material forming the member, the combination tending to cause the material to spring more or less energetically from any body within it formed and cast, when 65 the separator bolts have been withdrawn.

15. In a wall structure having within and at one of its surfaces rectangular block units arranged in flush horizontal and vertical alignment, each being exposed in the other surface of the 70 wall and therein having cut out end portions of inwardly curved horizontal profile creating in the associated blocks at each butt joining relatively wide but shallow channels, positioned at and substantially co-extensive with each channel a U-shaped pilaster member having leg portions ex-

tending outward from the wall and outwardly disposed flange portions in contact with the wall at and beyond the lateral extremities of the channel, attachment means such as anchors extending between the associated block members 5 and the pilaster members at each horizontal joint, insulating units such as cork board extending in uniform depth and in contact at one surface with the surfaces of the channel, but with clearance around each of the anchor arms, the combination 10 providing a formed space adapted to be filled with cementitious materials in forming walls of the type described herein.

16. In a wall construction of block units arranged in horizontal and vertical alignment 15 whose meeting faces are surfaced at a uniform depth with a felted substance such as mineral wool having a fill of a viscous substance such as a mixture of asphalt and mineral oil to form an integrally united juncture, structural members extending adjacent and in parallel relation with the butt joints of the block units, secured to and extending bilaterally from each structural member in each bed joint securing means such as anchors having perforated end portions, perforated metallic plates formed by the projections of the reinforcing members embedded in the block units, secured in adjacent portions of each adjacent and superimposed block unit with clearance recesses, locking pins inserted in the apertures of the 30 plates and anchors for positioning and securing the blocks units, the combination providing a rigid wall construction with building blocks joined together with a resilient and waterproof junction. 35

17. In a wall construction of block units arranged in horizontal and vertical alignment whose meeting faces are surfaced with a self-healing resilient material to form an integral juncture, structural members extending perpendicularly, 40 secured to and extending bilaterally from each structural member securing means such as anchors having perforated end portions, oppositely, in the end portions of the blocks perforated metallic plates formed by the projection of reenforcing members embedded in the block units, clearance grooves subjacent each plate, locking pins inserted in the apertures of the plates and anchor for positioning and securing block units to the structural members, the combination 45 providing a means for securing together block units with resilient waterproof junctures. 50

18. In a wall constructed of block units whose meeting faces are surfaced with a self-healing resilient material to form an integral juncture, 55 structural members extending in upright position to block units, secured to and extending bilaterally from structural members perforated metallic ears, perforated metallic bearing plates secured to the block units, locking pins for inserting in 60 the apertures of the interfitting plates and ears for positioning and securing block units together and to structural members, the combination providing a rigid wall construction of block units having resilient waterproof joints. 65

19. In a wall constructed of block units arranged in horizontal and vertical alignment, structural members extending adjacent and in parallel relation with butt joints, securing means such as anchors extending bilaterally from each 70 structural member in each bed joint having perforated end portions, perforated metallic bearing plates secured in adjacent portions of each adjacent and superimposed block with clearance grooves for inserting and withdrawing locking 75

pins, which plates are projections of the reenforcing members embedded in the block, the combination providing a rigid block unit fastened to structural members capable of withstanding lateral stress without rupturing.

20. In a wall constructed of block units arranged in horizontal and vertical alignment, structural members extending adjacent and in parallel relation with butt joints, anchor straps 10 extending at the joints bilaterally from structural members with perforated end portions projecting horizontally between perforated metallic plates secured in the blocks adjacent to joints, which plates are integrally connected to the reenforcing members embedded in the block units, grooved portions recessed in the block units subjacent to 15 facilitate the inserting and withdrawing locking pins driven through plates and anchor apertures, the combination providing a rigid construc-

tion for the block units capable of withstanding lateral stress without rupturing.

21. In a wall structure comprising block units at and within one flush surface and vertically disposed in spaced plurality within and at the other U-shape flange edged structural members, securing means such as strap anchors extending between the members and having notches forming grip keys at either end portion so as to slidably engage the flanged edge portions of the structural members causing the leg and back portions thereof to be restrained in a deformed drawn-together condition, the combination tending to cause the material of which the member is formed to spring more or less energetically away 10 from any substance within it formed and cast when the grip portions of the anchor keys have been removed. 15

WILLIAM E. DRUMMOND.
